US00D834128S

(12) **United States Design Patent** (10) **Patent No.:** **US D834,128 S**
(45) **Date of Patent:** **** Nov. 20, 2018**

(54) **CRUCIFORM SHAPED FLOTATION DEVICE**

(71) Applicants: **Stefan Janoski**, Tampa, FL (US);
Jessica Janoski, Tampa, FL (US)

(72) Inventors: **Stefan Janoski**, Tampa, FL (US);
Jessica Janoski, Tampa, FL (US)

(**) Term: **15 Years**

(21) Appl. No.: **29/611,773**

(22) Filed: **Jul. 25, 2017**

(51) LOC (11) Cl. **21-02**

(52) U.S. Cl.
